UNITED STATES PATENT OFFICE.

JULIUS J. PLANK, OF KANSAS CITY, MISSOURI.

AUXILIARY STEAM-GENERATOR.

1,089,076.

Specification of Letters Patent.

Patented Mar. 3, 1914.

Application filed February 1, 1912. Serial No. 874,747.

To all whom it may concern:

Be it known that I, JULIUS J. PLANK, a citizen of the United States, residing at Kansas City, in the county of Jackson and State of Missouri, have invented certain new and useful Improvements in Auxiliary Steam-Generators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an auxiliary steam generator and more particularly to the portable type of generators, being adapted for temporary location in the fire box of a locomotive for a period of time necessary for the quick generation of steam in the boiler of the engine, dispensing with the usual method of firing direct to the boiler, a practice involving a much greater duration of time.

A further object of my invention is to provide an auxiliary steam generator particularly adapted for oil burning locomotives, which will furnish steam for the blower and the oil atomizer and that can be readily inserted in the fire box as an integral unit and be quickly detached from its connections and removed, being used as the occasion requires, for the quick steaming of cold boilers.

It is obvious that my auxiliary steam generator is adapted for use in connection with other than locomotive engines, and can be used to generate quick steam in any type of engine, but I have specified an oil burning locomotive, knowing the difficulties encountered and the long time it takes in steaming up a cold boiler.

With this and other objects in view, the invention consists in certain constructions and in certain parts, improvements and combinations, as will be hereinafter described and specifically pointed out in the claims hereunto appended.

In the accompanying drawings which form a part of the specification—Figure I is a perspective view of a locomotive of the ordinary type with parts broken away and in section, showing the auxiliary steam generator positioned in the fire box thereof. Fig. II is a longitudinal elevation of the

auxiliary steam generator. Fig. III is a side view of the auxiliary steam generator. Fig. IV is a longitudinal section of the superheating tube. Fig. V is an elevation of the generator connection broken away to show the steam and water pipes and connections.

Referring more in detail to the parts:— 1 designates the locomotive boiler, 2 the saddle, 3 the platform, 4 the cab, 5 the tender, and 6 the fire box adapted to receive through the fire door 7, the auxiliary steam generator 8. The generator 8 preferably comprises a plurality of water tubes arranged in sets of two, designated 9—9', 10—10' and 11—11', a superheating tube 12 and a steam drum 13. The superheating tube 12 is centrally located between the said sets of tubes, being connected at its lower end to tube set 9—9' by a reducing coupling 12' and a special bushing 14, the nipple 15, and the four way coupling 16. The tube sets 10—10' and 11—11' are adapted for connection one with the other by a three way coupling 17 and the nipples 18 and 19, which take into the three way couplings 20 and 21, disposed on tubes 80 10 and 11. A threaded nipple 22 joins the coupling 17 with the four way coupling 16. The upper end of tubes 9—9', 10—10' and 11—11' are externally threaded at 23 to receive the reducing fittings 24, the said fitting having an enlarged lower end portion 25 interiorly threaded to engage the threaded portions 28 of the tubes, and having diminished opposite end portions 27 provided with openings arranged with screw 90 threads to engage the lower threaded ends 28 of the reducing pipes 29 which extend upwardly and parallel to the super-heating tube 12, being connected with the drum 13 which is spaced from the said superheating tube and positioned at the rear and adjacent the top portion thereof. The steam pipes 29 are of varied lengths, being substantially of much smaller diameter than those comprising the tube sets, and enter the drum 13 at 100 different points.

Threaded to the upper ends of the superheating tube and the drum, are the caps 30 and 31, apertured on their top portions to receive the pipe 31' and the nipple 32, which take into the elbows 33 and 34. The union 35 is connected with the elbows 33 and 34 by the nipples 36 and 37. The cap 30 of the superheating tube 12 is formed with an outwardly projecting portion 38 interiorly 110

threaded to receive the bushing 39 which is similarly threaded to receive the nipple 40 and an elbow 41 is connected to said nipple.

The pipe 42 connects the three way coupling 44 and the elbow 41, the lower part of the coupling having a bushing 44' adapted for receiving the nipple 45 of the valve 46, which is connected with the water supply reservoir 47 by the flexible pipe 48, the 10 elbow 49 and the pipe 50 which extends to a point adjacent the bottom of said water reservoir. The reservoir 47 is portable and adapted for location on either the platform 3 or on the tender 4, having a connection 47' on its upper end, and having a bushing 51 which takes into the three way coupling 53. A threaded plug 52 is mounted in the upper 20 part of the three way coupling 53, and adapted to be detached therefrom, whereby the reservoir can be filled with water. The pipe 47' is disposed on said reservoir, and is threaded to the lower part of the three way coupling 53.

Connected with the middle part of coupling 53, is the flexible pipe 55, which in turn is suitably connected with the pump 56, adapted to draw the water supply from the tender reservoir, through the flexible pipe 57. An air gage 58 is arranged on the portable reservoir 47, by which the air pressure is ascertained.

59 designates the fountain head which is connected with the live steam chamber of the boiler, being provided with a globe valve 60, and a pipe 61, which connects the fountain head with the manifold 62, comprising a plurality of couplings 63—64—65—66 and 67, which have steam pipe connections 68—69—70 and 71, are provided with globe valves 72 and extend respectively to the blower 73, the atomizer 74, the flusher 75, and the oil tank heating pipe 54; the said connections, valves, fountain head, blower, atomizer, flusher and heater being a part of the regular equipment of an oil burning locomotive. The elbow coupling 67, which forms a part of the auxiliary steam generating equipment, couples to the manifold 62 and is threaded to receive the flexible pipe 77, which, at its lower end, is connected with the three way coupling 44, by the union 77' and has a safety valve 78 disposed on the upper end thereof.

Disposed on the special bushing 14 is the water supply pipe 79, which connects at its lower end with the water tubes 9—9', 10—10', and 11—11', and extends upwardly through the superheating tube 12, the member 38, the bushing 39, the nipple 40, elbow 41, the pipe 42, coupling 44 to the valve 46, connecting with the flexible water pipe 48.

80 designates the oil supply valve, having an operating handle 81 and pipes 82 and 83, leading to the oil tank in the tender 5 and the atomizer 74.

In order to generate steam quickly in a cold boiler with my improved device, the generator is inserted through the fire door 7 and placed in an upright position on the floor of the fire box 6, with the pipe 42 extending through an aperture provided in the fire door. The globe valve 60 is operated to shut off the fountain head 59, and the flexible pipe 77 is coupled to the elbow coupling 67 on the manifold. The oil supply valve is operated by handle 81 to provide a flow of oil to the atomizer; the pump 56 is operated to draw water from the tender tank to the air tight reservoir 47, forming a pressure for forcing the water through the water pipe 48, the regulating valve 46, the elbow 41, and through the pipe 79 in the superheater tube 12, to the tubes 9—9', 10—10' and 11—11' until the water reaches the center of the tubes. Waste is thrown into the fire box in the immediate proximity of the generator and lighted. After a short period the water in said tubes is converted into steam which rises and forces its way through the reducing fittings 24 into the reducing pipes 29 and to the drum 18, from which point it forces its way through the connections on the caps 30 and 31 of the drum and the superheating tube through the pipe 31' and into the superheater tube, and from there it is delivered through the pipes 42 and 77 to the manifold 62. At this point the valve 72 of the blower connection and the valve 72 of the atomizer connection are opened so that the steam generated in the auxiliary generator will provide a flow of steam for the atomizer to form an igniting mixture and a forced draft for the blower. The safety valve 78 is adapted to relieve the auxiliary generator of any over pressure of steam. When sufficient steam has been generated in the engine boiler the valve 72 is closed, the pipe 77 is detached from the valve 72 and then from union 77', and after being flushed with cold water through pipe 48, the pipe 48 is then disconnected from coupling 44 and the pipe 42 is swung upward and the auxiliary generator is removed from the fire box by grasping the union 35 and together with its connections and the water reservoir 47 is disposed on the tender, the atomizer and the blower meanwhile being supplied with steam from the engine boiler.

It is obvious with my generator a cold boiler can be fired to generate steam in a much shorter time than heretofore.

It is possible with my device to dispense with the portable reservoir and tender water supply, by directly connecting the pipe 42 of the generator with the ordinary water pressure service that is generally found in railroad yards, the ordinary pressure system now universally used being powerful enough to force the needed supply to the generator.

Having thus described my invention, what I claim as new therein and desire to secure by Letters-Patent is:

1. The combination with a steam boiler, of an auxiliary steam generator removably located in the fire box of said boiler. 45
2. The combination with a steam boiler, of an oil burner, and an auxiliary steam generator removably mounted in the fire box 10 of the boiler and connected with said burner.
3. The combination with a steam boiler, of an oil burner having a steam line to the boiler, and an auxiliary steam generator removably mounted in the fire box of the boiler 15 and connected with said steam line.
4. The combination with a steam boiler and a burner, of a removable steam generator adapted for location within the fire box of the boiler, and comprising a plurality of steam tubes, a superheating tube and drum, and means for conducting steam from the generator to the burner. 55
5. The combination with a steam boiler, of a removable steam generator, comprising a plurality of heating tubes, a superheating tube and a drum, and a heater for generating steam in the tubes and superheating same in the superheating tube. 60
6. The combination with a steam boiler and a burner, of a removable steam generator comprising a plurality of generating tubes, a superheating tube and a drum, means for generating steam in said tubes and heating the steam in said superheating tube, and means for conducting steam from the superheating tube to the burner. 65
7. The combination with a steam boiler and a burner, of a removable steam generator, comprising a plurality of steam generating tubes, a drum and a superheating tube, 70

means for generating steam in said tubes, heating same in said drum and superheating the steam in the superheating tube, and means for conducting steam from the superheating tube to the burner. 75

8. The combination with a steam boiler and a burner, of a removable steam generator comprising a plurality of steam generating tubes, a drum and a superheating tube, a plurality of pipes connecting the tubes 50 and drum, a connection between the drum and the superheating tube, means for supplying water to said generator, and means for conducting steam from the superheating tube to the burner. 80

9. The combination with a steam boiler and a burner, of a removable steam generator located in said fire box, comprising a plurality of water tubes, a drum and a superheating tube, means for supplying water to said tubes, and means for conducting steam to said superheating tube and from the superheating tube to the burner. 85

10. The combination with a furnace fire-box, of a liquid fuel burner for said furnace fire-box, means for supplying oil to said burner, and means for supplying steam from two different sources to said burner, said means including a supply pipe leading from one source and connected to the burner, the other source comprising a steam generator located in the fire-box and heated by the burner and having a steam outlet pipe connected to said supply pipe. 90

In testimony whereof I affix my signature in presence of two witnesses.
